DRILLING MACHINE

Elmer Joseph Bentley and Campbell Young,
Paterson, N. J.

Application November 30, 1942, Serial No. 467,392

6 Claims. (Cl. 77—22)

This invention aims to provide a novel instrumentality whereby a line of holes may be bored in a work piece, it being possible to rotate the work piece on its axis, to present different portions thereof to the action of the drills, and it being possible to reciprocate the work piece, for a like purpose, if the work piece is flat.

The shifting of the drills with respect to the work piece is brought about by a plurality of carriages, interengaged with each other, and with the supporting frame, in a novel way, and novel means is provided for advancing the drilling mechanism with regard to the work.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in top plan, a device constructed in accordance with the invention;

Fig. 2 is an end elevation;

Fig. 3 is a front elevation;

Fig. 4 is a transverse section;

Fig. 5 is an end elevation showing a modification;

Fig. 6 is a vertical section on the line 6—6 of Fig. 5.

In Fig. 1, which is a top plan, the letter F marks the front of the machine, and the letter B marks the back thereof. As hereinafter employed, the word "transverse" means from front to back. In Fig. 3, which is a front elevation, the operator generally stands about where the legend "Fig. 3" appears, and "longitudinal" means to the right hand or to the left hand of the operator.

The machine comprises a frame 1, which may be constructed as desired. Specific portions of the frame will be mentioned if they attain consequence. Until notice, the description will read on Figs. 1 to 4.

The frame 1 supports transverse tracks 2, disposed at the ends of the frame. A carriage 3 is provided and in its side portions are journaled axles 4, carrying grooved wheels 5, adapted to roll

along the tracks 2. The carriage 3 moves transversely of the machine, that is from front to back thereof. The carriage 3 includes longitudinal tracks 6. The carriage 3 has a rearward extension, including transverse rods 7, a longitudinal front cross bar 8, and a longitudinal rear cross bar 9, connected to the rods 7.

The horizontal table 10 is located at the front of the machine and is mounted upon the frame 1, between the tracks 2. A template 11 is firmly but detachably mounted on the table 10 and has holes or seats 12, laid out in accordance with the job of boring which is to be done.

A carriage 14 is provided, and has grooved wheels 15, movable along the tracks 6. The carriage 14, therefore, is adapted to move longitudinally of the machine. The carriage 14 includes a top plate or transverse arm 16, to which is secured a bracket 17, that extends forwardly, downwardly, and again forwardly, as shown in Figs. 2 and 4. An arm 18 is hinged at 19 to the bracket 17, for vertical swinging movement, and is supplied with a handle 20. Near its forward end, the arm 18 carries a depending stylus, passing through the lower, forward part of the bracket 17 and adapted to enter any selected one of the openings 12 in the template 11.

The rear end portion of the top plate 16 of the carriage 14 extends well within the frame 1, as in Fig. 4 shows, a spacer 22 being mounted on the part specified, a plate 23 being superposed on the spacer, and the parts 16, 22 and 23 being held together by securing elements 24. Near its edges, the plate 23 is provided with grooved wheels 25, mounted to rotate on vertical axes.

The end portions of the frame 1 are connected by tie bars 26, to which longitudinal tracks 27 are secured. The numeral 28 marks a carriage provided with grooved wheels 29, mounted to roll along the tracks 27, the carriage 28 having movement longitudinally of the machine. The carriage 28 is supplied intermediate its ends with a depending extension 30, extended downwardly between the tracks 27 and provided at its lower end with transverse guides 31, preferably I-beams, the wheels 25 of the carriage 14 being disposed between the lower flanges of the guides, in engagement therewith. Near its ends, as shown in Fig. 3, the carriage 28 is provided with transverse tracks 32, preferably in the form of channels, intermediate tracks 33, preferably inverted T-members, being secured to the carriage.

The numeral 34 designates a truck, comprising transverse end pieces 35, connected by longi-

55

tudinal rods 36, axles 100 being journaled in the end pieces, the axles carrying grooved wheels 37, the tracks 32 and 33 of the carriage 28 being engaged with the wheels, to support the truck 34.

The numeral 38 designates a tool carriage which has movement transversely of the machine, that is, from front to back. The tool carriage 38 includes longitudinal sills 39, to which depending transverse tracks 40 and 41 are secured, the tracks 40 being shaped like the tracks 32 of the carriage 28, and the tracks 41 being shaped like the tracks 33 of that carriage. The depending flanges of the tracks 40 and 41 are received in the grooved wheels 37 of the truck 34.

A framework 42 is assembled with the sills 39 of the tool carriage 38, and drilling mechanisms 46 are mounted on the framework, the drilling mechanisms including spindles 43, with which horizontal, rearwardly projecting drills 44 are assembled, the drilling mechanisms being driven by electric motors 45, or in any other desired manner.

Figure 2 shows that standards 47 are secured to the tracks 32 of the carriage 28, near the forward ends of the tracks. Spring adjusters 48 are mounted in the standards, the forward ends of pull springs 49 being connected to the adjusters, the rear ends of the springs being anchored at 50, on the tracks 40 of the tool carriage 38.

It is evident from an inspection of Figs. 2 and 3 that the drills 44 are intended to perforate a piece of work 51, which may be a bar or pipe. The work piece 51 is carried by a shaft 53, journaled in bearings 54 located at the top of the frame 1 at the ends thereof and near the back of the frame. The work piece 51 is rotated, to present different portions of it to the drills 44.

The means for rotating the shaft 53 and work piece 51 may comprise pulleys 55, secured to the shaft 53 inwardly of the ends of the main frame 1 of the machine, a flexible element 56, such as a belt, being looped about each pulley. Below the work piece 51, the belts are crossed as shown at 57 in Fig. 2. Tighteners 58 are mounted on rear cross bar 9 of the carriage 14, the rear ends of the flexible elements 56 being connected to the tighteners. The forward portions of the belts 56 move over direction changing idlers 59 on the ends of the frame 1 and are extended horizontally and forwardly, the forward ends of the belts being connected at 60 to the cross bar 8 which forms part of the carriage 3.

The springs 49 of Figs. 2 and 1 constitute means for retracting the tool carriage 38. For the advancement of the tool carriage 38, to cause the drills 44 to be fed into the work 51, there is provided a means under the control of an operator and next to be described.

A pedal 61 is hinged at 62 to the floor of the shop in which the machine is mounted, and extends backwardly from the hinge. The pedal is raised by means of a pull spring 62', or a pair of such springs, having their upper ends secured to the tracks 2 on the frame 1. The forward ends of flexible elements 63 are attached to the rear portions of the pedal 61, and pass upwardly and rearwardly over idlers 64, mounted to rotate on the frame 1. The flexible elements 63 extend upwardly, around idlers 65 at the lower, rear portion of the frame 1 and extend forwardly, at the top of the frame, over idlers 66 on the frame. The upper, forward ends of the flexible

elements 63 are attached to bearings 68, in which a shaft 67 is mounted to rotate.

The shaft 67 is mounted in bearings 72 (Fig. 4) retained at 73 in extensions 69 (Figs. 1 and 4) on the rear ends of the tracks 40 of the tool carriage 38. Between the belts 56 (Fig. 3) and the end portions of the main frame 1, grooved wheels 70 are mounted rotatably on the shaft 67 and are so located as to roll along short tracks 71 on the ends of the main frame, the tool carriage 38 thus being given added support directly below the spindles 43 of the drilling mechanisms 46.

Referring particularly to Fig. 2, and assuming that the stylus 21 is in one of the seats 12 of the template 11, the operator depresses the pedal 61, and the springs 62' are put under tension. The flexible elements 63 run over the sheaves 64, 65 and 66, and the tool carriage 38 is carried rearwardly, the tool carriage being supported on the wheels 37 of the truck 34. This operation elongates the springs 49. The drills 44, operated by the motors 45, form a line of holes in the work piece 51, longitudinally thereof.

The pedal 61 is released, and swings upwardly, under the impulse of the springs 62'. The springs 49 move the tool carriage 38 forwardly, and the drills 44 are retracted with respect to the work piece 51. As the carriage 38 moves forwardly, the flexible elements 63 pass over the sheaves 64, 65 and 66.

In order to bore more holes in the work piece 51, in the same longitudinal row, the operator swings the arm 18 upwardly, by means of the handle 20, until the stylus 21 is clear of the seat 12 which it formerly occupied in the template 11. Using the handle 20, the operator moves the carriage 14 lengthwise of the machine, to a selected position, the carriage wheels 15 traveling along the tracks 6. The arm 18 is swung downwardly until the stylus 21 enters a selected seat 12 in the template 11. The carriage now is fixed in a new position, longitudinally of the machine.

Referring to Fig. 4, when the carriage 14 moves lengthwise of the device, the top plate 16 of the carriage, the plate 23 thereon, the wheels 25, the guides 31 on the extension 30 of the carriage 28, and the body of the carriage 28 are moved longitudinally of the machine. At this time, the wheels 25 which, in effect, are mounted on the carriage 14, do not move transversely, that is from front to back, on the guides 31, which are indirectly secured to the carriage 28.

When the carriage 28 moves longitudinally, the tool carriage 38 moves longitudinally of the machine, also, since the wheels 37 of the truck 34 are engaged with the tracks 32 and 33 (Fig. 3) of the carriage 28, and with the corresponding tracks 40 and 41 of the carriage 38. The drills 44 are moved longitudinally of the machine.

The operator depresses and then releases the pedal 61, the drills 44 being advanced into the work piece 51, and being withdrawn therefrom, in the manner hereinbefore described.

Suppose that it is desired to rotate the work piece 51 on its horizontal axis, thereby to present a new portion of the work piece to the drills 44, in order to bore another line of holes extended longitudinally of the work piece, but spaced, circumferentially of the work piece, from the lines that have already been bored.

Through the instrumentality of the handle 20, the arm 18 is swung upwardly, to remove the stylus 21 from the seat 12 which it occupied in

the template 11. The operator pushes rearwardly on the handle 20, the wheels 5 of the carriage 3 moving rearwardly on the tracks 2 of the frame 1. The arm 18 is swung downwardly, to engage the stylus 21 in another seat 12 of the template 11, considered relatively to the front and the back of the machine.

The flexible elements 56 impart rotation to the pulleys 55 and to the shaft 53, a new portion of the work piece 51 now being presented to the drills 44. The operator depresses and then releases the pedal 61, and the work piece is bored, in a way hereinbefore set forth.

When the carriage 3 moves from front to back, there is a front to back movement imparted to the carriage 14, because the grooved wheels 15 of that carriage are engaged with the tracks 6 of the carriage 3. There is no corresponding movement from front to back in the carriage 28, due to the operation of the pedal 61, because the wheels 25, assembled with the carriage 3, can roll along the guides 31 that are connected to the carriage 28: nor does the carriage 14 have a front to back movement, relatively to the carriage 3, because the wheels 15 of the carriage 14 are engaged with the tracks 6 of the carriage 3.

The work piece 51 may be perforated, both longitudinally and circumferentially, by the manipulation of two parts, to wit, the pedal 61 and the handle 20.

Passing to the form depicted in Figs. 5 and 6, parts hereinbefore described have been designated by numerals already used, with the suffix "a."

The frame 1a of the machine includes uprights or guides 74, sustained by inclined braces 75. A vertically movable support for flat work is provided, and may be in the form of a plate shown at 76. The plate 76 has wheels 77, mounted to move along the guides 74.

Adjacent to their upper ends, the uprights are connected by a cross tie 78, on which are journaled inner pulleys 79. The cross tie 78 projects outwardly beyond the guides 74, and on the outwardly projecting portions of the cross tie are journaled outer pulleys 80. Flexible elements 81 are extended across the pulleys 79 and 80, and to the outer ends of the flexible elements are secured counterweights 82, or equivalent devices. The inner ends of the flexible elements 81 are secured at 83 to the upper portion of the work support 76. The function of the counterweights 82 and associated parts is to aid in the raising of the work support 76.

An upper horizontal shaft 84 and a lower horizontal shaft 85 are journaled for rotation on the guides 74. The shaft 85 carries outer band wheels 86, and inner band wheels 87, the shaft 84 carrying band wheels 88.

Flexible elements or bands 89 are provided, and have their lower, forward ends attached to the carriage 3a, as shown at 8a—60a in Fig. 5. The bands 89 extend backwardly and upwardly over the band wheels 86, and thence downwardly over the band wheels 88, the lower ends of the bands being secured at 90 to the upper portion of the work support 76. Bands 91 are provided, and have their upper ends secured to the lower portion of the work support 76, the bands proceeding downwardly and rearwardly, around the band wheels 87, the rear ends of the bands being secured to the parts 1a of the carriage 3a, as shown at 9a in Fig. 5. In substance, each band 91 and

the corresponding band 89 form one band, in which the work support 76 is interposed.

Reciprocation of the carriage 3a causes an up and down movement of the work support 76, to present different portions of the work support and the work upon it to the drills 44a, the machine of Fig. 5 operating practically like the one shown in Fig. 2, aside from the fact that, in Fig. 2, the work piece 51 is rotated on its axis, whereas the work holder 76, adapted to retain a flat piece of work, has right line movement.

For convenience in claiming the invention, the carriage 3 may be called a supporting carriage, the carriage 14 being an operating carriage, and the carriage 28 being a conveyor carriage. The several carriages are wheel-mounted, and friction is reduced to such an extent that the machine may be handled by a single operator, the pedal 61 being actuated by his foot, the handle 20 and the connected parts being manually operated. In both forms of the invention, the work holder is movably mounted on the frame. In the form shown in Figs. 1 to 4, the work holder is the shaft 53, and its movement is that of rotation. In the form shown in Figs. 5 and 6, the work holder is shown at 76, and its movement is a right line sliding movement.

Having thus described the invention, what is claimed is:

1. In a drilling machine, a frame, a supporting carriage mounted on the frame for movement transversely thereof, an operating carriage mounted on the supporting carriage for movement longitudinally of the frame, a conveyor carriage mounted on the frame for movement longitudinally thereof, a slidable connection between the operating carriage and the conveyor carriage and disposed transversely of the frame, the connection joining the operating carriage and the conveyor carriage together for movement together longitudinally of the frame and to permit the conveyor carriage to move relatively to the operating carriage and transversely of the frame, a tool carriage, means for mounting the tool carriage on the conveyor carriage for movement transversely of the frame, drilling mechanism on the tool carriage, a work holder movably mounted directly on the frame, in operative relation to the drilling mechanism, and mechanism extended transversely of the frame, and connected to the supporting carriage and to the work holder, for moving the work holder to present a new portion of the work to the drilling mechanism, when the supporting carriage is actuated.

2. A drilling machine constructed as set forth in claim 1, and wherein the means for mounting the tool carriage on the conveyor carriage comprises tracks mounted on those carriages, transversely thereof, and a freely movable truck interposed between those carriages and having wheels engaged with the tracks against movement longitudinally of the frame.

3. A drilling machine constructed as set forth in claim 1, and wherein the work holder comprises a shaft supported for rotation on the upper portion of the frame, a pulley on the shaft, and a flexible element engaged with the pulley and having its ends connected to the supporting carriage at widely spaced points transversely of the machine, the flexible element being crossed upon itself below the pulley, and the specified location of the shaft serving to elevate the work on the shaft, for ready inspection.

4. In a drilling machine, a frame, upright guides located adjacent to the ends of the frame, a vertically-movable, transverse work support having its ends slidably mounted on the guides, a carriage mounted on the frame for sliding movement toward and away from the support, a boring mechanism upheld by the carriage for sliding movement transversely of the frame and so located as to cooperate with work on the support, a flexible element having its ends extended in opposite directions transversely of the frame and connected to the carriage at spaced places, the intermediate portion of the flexible element forming an upright loop in one portion of which the support is interposed, and means carried by the uprights and engaging the flexible element to produce the loop and to maintain the ends of the flexible element in the position stated.

5. In a drilling machine, a frame, an operating carriage, means for mounting the carriage for straight line movement transversely of the frame and for straight line movement longitudinally of the frame, the carriage having a transverse arm prolonged backwardly into the frame, spaced tracks extended longitudinally of the frame, a conveyor carriage mounted to move along the tracks and provided with a depending extension disposed between the tracks and extended downwardly therebelow, transverse guides carried by the extension and located below the tracks, the guides extending forwardly and rearwardly beyond the tracks, the conveyor carriage being slidably engaged with the guides, a boring mechanism supported on the conveyor carriage, and means on the frame for holding a work piece in the field of operation of the boring mechanism.

6. In a machine for boring an approximately cylindrical piece of work transversely, under the guidance of a flat template, a frame, a work-piece holder journaled on the frame for rotation about a substantially horizontal axis, a substantially horizontal template support on the frame, a carriage, a stylus supported on the carriage in such position that it cooperates with a template on the template support, a boring mechanism so disposed as to cooperate with a work piece on the holder, a movable means, one portion of which mounts the boring mechanism on the frame for straight line sliding movement transversely of the frame, to advance the boring mechanism with respect to a work piece on the holder, another portion of the movable means mounting the boring mechanism on the frame for straight line sliding movement longitudinally of the frame, to shift the boring mechanism to a new place with respect to a work piece on the holder, means for mounting the carriage for straight line sliding movement longitudinally of the frame and for straight line sliding movement transversely of the frame, the carriage being engaged with said other portion of the movable means, for straight line sliding movement transversely of the frame, mechanism for rotating the holder, responsive to the movement of the carriage transversely of the frame, and mechanism for actuating said one portion of the movable means, to advance the boring mechanism, the actuating mechanism terminating in a part located so close to the stylus that the stylus, said part, and the carriage, may be controlled by one operator occupying a single position.

ELMER JOSEPH BENTLEY.
CAMPBELL YOUNG.
